UNITED STATES PATENT OFFICE.

CLIFTON ROSS, OF UTICA, MISSISSIPPI.

SCRUB-BOARD.

1,198,963.

Specification of Letters Patent. Patented Sept. 19, 1916.

Application filed June 30, 1916. Serial No. 106,859.

To all whom it may concern:

Be it known that I, CLIFTON ROSS, a citizen of the United States, residing at Utica, in the county of Hinds and State 5 of Mississippi, have invented certain new and useful Improvements in Scrub-Boards; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to new and useful improvements in scrub boards and consists of a simple and efficient device of this nature so arranged that the various parts may 20 be easily disconnected so that they will thoroughly dry. Heretofore, in the making of scrub boards, the parts were rigidly secured together, thus allowing water and foreign matter to get into the cracks and thereby 25 produce decay of the same.

My invention is illustrated in the accompanying drawings, in which:—

Figure 1 is a face view of a scrub board made in accordance with my invention. 30 Fig. 2 is a sectional view on line 2—2 of Fig. 1, a rod connecting the side rails and fastening means therefor being removed. Fig. 3 is a detail view of one side of the board showing a channel in the end face 35 thereof. Fig. 4 is a sectional view on line 4—4 of Fig. 1.

Reference now being had to the details of the drawings by letter, A, A designate the opposite side rails of the board, having 40 a longitudinal channel B formed in the inner face thereof, as shown clearly in the drawings. Said channel is provided with a shoulder D near one end and each has a screw eye E secured to its inner face. The 45 board is designated by letter H and has a series of projections I upon the face thereof, arranged in staggered relation to one another and which are formed by pieces of wire which are bent at right angles, as 50 shown in Fig. 4, and passed through the board, while their inner ends, designated by letter J, are flared and serve as means for securely holding the same in place. A partition, designated by letter O, is held to the

board by means of the clenched pins R and a 55 slight space intervenes between said bar O and the face of the board, as shown in Fig. 2 of the drawings, sufficient to allow any drippings from the upper portion of the board, designated by letter P, which forms 60 a soap receptacle, to pass therethrough. The portion of the board above the partition O has vertically disposed projections Q against which the bars of soap are adapted 65 to rest.

It will be noted that the opposite edges of the board are provided with shoulders T, adapted to engage the shoulders D formed on the inner faces of the side rails A and eye bolts, designated by letter S, are passed 70 through the side rails, a spring S' being secured at one end to one of said bolts and at the other end to a rod S² which has a hook S³ for engagement with the other of said eye bolts S, as shown clearly in dotted lines 75 in Fig. 1 of the drawings. Other eye bolts, designated by letter L, are passed through the side rails adjacent the lower portion thereof and are connected together by the rod L'.

In assembling the parts, it will be noted that the two side rails receive the opposite edges of the board H, the edges engaging the channels and said side rails are held in place through the medium of the eye 85 bolts and rods connected thereto. When it is desired to disassemble the parts, the hook rod S² is released from the eye bolt S, allowing the side rails to swing in the manner shown in dotted lines in Fig. 1 of 90 the drawings, thus allowing all of the parts to thoroughly dry and thereby extend the life of the board and form a means whereby any part may be thoroughly cleansed of any foreign matter.

What I claim to be new is:—

A scrub board having shoulders upon the opposite edges thereof, side rails having longitudinal channels in the inner faces thereof, said channels extending substantially the length of the board and through corresponding ends of the rails, a head channeled to receive one end of the board, each channel in the side rails having a shoulder adapted to be engaged by a shoulder upon 100 the edge of the board, screw eyes passing through the rails below the board, a rod connecting the eyes of said bolts, other eye 105

bolts passing through the rail intermediate
the shouldered portion of the rails and the
head, a spring connected to one of said eye
bolts near the upper end of the board, a rod
5 connected to said spring, and another eye
bolt in the opposite rail engaged by said
hook.

In testimony whereof I hereunto affix my
signature in presence of two witnesses.

CLIFTON ROSS.
